YARN CONTROLLING DEVICE

Isaac H. C. Green, Pawtucket, R. I., assignor to
Hemphill Company, Central Falls, R. I., a cor-
poration of Massachusetts

Application March 17, 1950, Serial No. 150,329

3 Claims. (Cl. 66—138)

1

This invention relates to a new and useful improvement in yarn controlling devices and, in particular, devices for controlling the yarns at a certain point of knitting of so-called solid color patterned fabric by automatic multi-feed machines such as that disclosed and claimed in U. S. Letters Patent #2,217,022 to which an automatically produced, rotary knit, inlaid or knit-in elastic top has been added.

As described in the patent referred to, the patterned portions of the fabric are knit in the reciprocatory manner of a plurality of yarns all of which are knit during each stroke of the cylinder but independently and each in a fraction only of the circumference of the fabric, the several fractions being connected to adjacent portions by true sutures. During such knitting the several yarns tend to wind about each other as shown, for example, in Fig. 1 of the above patent but, since the knitting is reciprocatory, this winding is dissipated during each knitting stroke to be followed by a similar winding in the opposite direction. Such winding creates no difficulty with respect to the proper feeding of the several yarns which, consequently, require no special control in this respect. However, when the stocking is started as by knitting a knit-in or inlaid elastic top in the rotary manner, all of the other yarns, with the exception of the body yarn being out of action, wind around each other continuously throughout the knitting of the top. The result is that when the introduction of one of these other yarns is attempted it may well be that the yarn with which it is interwound and which is still out of action will prevent it from following its yarn lever downwardly sufficiently to enable it to be caught by the needles. In particular, this is likely to happen at the beginning of the leg just after the elastic yarn feed has been withdrawn because then to the winding of the yarns referred to above is added the upward pull of the elastic. The purpose of this invention is to provide means for pushing the twisted idle yarns downwardly into the cylinder a sufficient distance so that the twist adjacent the yarn levers is eliminated or so lessened that a yarn lever can drop its yarn into needle taking position without interference from another yarn.

One form of the invention is shown in the drawings of which:

Fig. 1 is a general view partly in section showing this invention in operation to project the idle yarns into the cylinder as just described to assure that any one of them will be in position to be

2

taken by the needles when its lever is moved into action;

Fig. 2 is a view of part of a mechanism by which this device may be operated; and

Fig. 3 is a view illustrating other parts of this operating mechanism.

As shown in Figs. 1 and 2, the device consists of a flat finger-like pusher 1, the lower end 2 of which is so shaped and positioned as to be engageable with the idle yarns 3 within the cylinder when they have been wound together as already described. Its operative position is shown in full line in Fig. 1. Its idle position is shown in dot and dash lines. Pusher 1 is attached to a slide 4 which is vertically slidable in suitable guides such as 5 and 6 in a bracket 7. Slide 4 is provided with a stud 8 in pivotal and slidable contact with an arm 9 which is pivoted at 10 on bracket 7 and the other end of which is similarly connected to one end of an arm 11. Arm 11 is pivoted to the bracket 7 at 12 and the other end 13 is pivotally connected to a vertically movable rod 14. A collar 15 is affixed to rod 14 adjacent its lower end and above this collar is slidably mounted on rod 14 a block 15a which is rigidly connected to rod 16. Rod 16 is pivotally connected to one end of a rocker 17, the other end of which is associated with a pattern drum 18.

The primary duty of rod 16 is to move elastic yarn feed 19 into and out of yarn feeding position. In the arrangement shown it is assumed that, when the end of rocker 17 rests upon the surface of drum 18, the elastic yarn feed is down in its yarn feeding position for the making of the elastic top. When the top is completed and the elastic yarn is to be taken out, rocker 17 is raised by cam 20 on drum 18. However, the move of the drum at this point is of such length that rocker 17 will not only be raised onto cam 20 but will also be raised still higher on to cam 21 and will then be dropped off this cam to the full line position shown in Fig. 3. This additional raising of rocker 17 will raise the elastic yarn feed still higher but this is immaterial since the elastic yarn is out of action. It will also supply the necessary movement to rod 14 through rod 16, block 15a, collar 15 and the linkage described to move the pusher 1 from its inoperative position shown in dot and dash in Fig. 1 to its operating position shown in full line in that figure. The parts of the operating mechanism will then be in the dotted line position shown in Fig. 3 and the full line position shown in Fig. 2. Since rocker 17 is moved from a position upon the surface of drum 18 to the tops of cams 20 and 21 and back again

to the top of 20 where it is shown in full line in Fig. 3 by a single move of drum 18, if the operation of pusher 1 depended entirely upon rocker 17 its operating period could not be properly timed. To obviate this difficulty, a latch 22 is pivotally attached to a suitable part of the machine and is adapted to engage a pin 23 affixed to rod 16. When rod 16 is lowered by the lifting of rocker 17 by cam 21, the latch 22 will engage pin 23 and will thereafter retain rod 16 in down position although rocker 17 is no longer riding upon cam 21. Thus pusher 1 may be maintained in its operating position as long as desired. As a rule, this need be for only a fraction of one reciprocation of the machine. The means by which latch 22 is tripped so that rod 16 and, consequently, rod 14, the linkage 11 and 9 and pusher 1 can move into their inoperative positions shown in dot and dash in Figs. 1 and 2 consists of a small drum 24 adapted to rotate at the same angular speed as the cylinder. Drum 24 is provided with a roller 25 adapted to engage and swing down the tail 26 of latch 22 so that it will release rod 16 by assuming the position shown in dotted line in Fig. 2.

It will be understood, of course, that when pusher 1 is in its inactive dot and dash line position the yarns will occupy a position considerably higher adjacent the center of the cylinder than that shown in Fig. 1. To avoid confusion, this is not shown. Also, it will be understood that the fabric being knit will rest upon the sinkers and will extend downwardly into the cylinder in the usual way. The fabric also has been omitted for the same reason. While this invention has been described in connection with the specific and unique machine disclosed and claimed in the patent referred to, it will be understood, of course, that its scope is not limited by such descriptive association but extends to any other situation in which it may be used to advantage.

I claim:

1. In a knitting machine having a cylinder, needles and yarn levers and in which yarns from a plurality of yarn levers become wound together adjacent the center of the cylinder so that individual yarns may be prevented from being taken by needles when the respective yarn levers are brought into action, means for pushing such interwound yarns downwardly into the cylinder so that additional yarn is drawn through each yarn lever and the interwinding correspondingly lessened adjacent the yarn levers so that a yarn when its lever is moved into

operating position will follow it to a position at which the yarn can be taken by the needles and means for actuating said pushing means at a predetermined time in relation to the knitting by the machine.

2. In a knitting machine having a cylinder, needles and yarn levers and in which yarns from a plurality of yarn levers become wound together adjacent the center of the cylinder so that individual yarns may be prevented from being taken by needles when the respective yarn levers are brought into action, means for pushing such interwound yarns downwardly into the cylinder so that additional yarn is drawn through each yarn lever and the interwinding correspondingly lessened adjacent the yarn levers so that a yarn when its lever is moved into operating position will follow it to a position at which the yarn can be taken by the needles and means for actuating said pushing means at a predetermined time in relation to the knitting by the machine.
3. In a knitting machine having a cylinder, needles and a plurality of yarn feeding stations each provided with a plurality of yarn levers and in which yarns from levers at each feeding station becomes wound together adjacent the center of the cylinder so that individual yarns may be prevented from being taken by needles when the respective yarn levers are brought into action, means for pushing such interwound yarns downwardly into the cylinder so that additional yarn is drawn through each yarn lever and the interwinding correspondingly lessened adjacent the yarn levers so that a yarn when its lever is moved into operating position will follow it to a position at which the yarn can be taken by the needles and means for actuating said pushing means at a predetermined time in relation to the knitting by the machine.
